UNITED STATES PATENT OFFICE.

FRANK H. CHAMBERLIN AND RAYMOND H. COLEMAN, OF CLEVELAND,
OHIO.

TELEPHONE ATTACHMENT.

SPECIFICATION forming part of Letters Patent No. 766,929, dated August 9, 1904.

Application filed March 10, 1903. Serial No. 147,181. (No model.)

To all whom it may concern:

Be it known that we, FRANK H. CHAMBERLIN and RAYMOND H. COLEMAN, citizens of the United States, residing at Cleveland, in the county of Cuyahoga and State of Ohio, have invented a certain new and useful Improvement in Telephone Attachments, of which the following is a full, clear, and exact description, reference being had to the accompanying drawings.

This invention relates to an attachment adapted to be used with a telephone and carry the names and numbers of the most usual calls.

15 The object of the invention is to provide such an attachment in a form which will be cheap in construction, neat in appearance, and in which the names on the indicator shall not be ordinarily visible.

20 To this end the invention consists of a roller having attached thereto a flexible strip carrying the names and numbers, means for rotating the roller in the direction to wind up the strip, a casing covering said parts and having a slot through which the strip passes, and a suitable bracket for supporting these members.

The more specific embodiment of the invention shown herein is also of our invention.

30 The invention is clearly illustrated in the drawings, wherein—

Figure 1 is a front elevation of a desk-telephone with our attachment applied to it. Figs. 2 and 3 are cross-sections of the attachment on the lines 22 and 33, respectively, of Fig. 1.

Referring to the parts by letters, A represents the vertical standard of a desk-telephone. B is a bracket, which is clamped thereto by means of a clamping-plate B', bolts b, and butterfly-nuts b'. This arrangement allows the bracket to be adjusted to the desired height. Carried by the upper end of the bracket is a horizontal stationary rod C. On this rod is loosely mounted the spool D, having flanges d d' at its ends. Beyond one end of the spool is a spiral spring E, the inner end e of which takes into an opening in the rod and the outer end e' of which is secured

to the flange d' of the spool. By this means 50 the spool is given a tendency to return to normal position if rotated therefrom.

Surrounding the rod C against the outer face of the standard B is the cap F, which has a perforated flange. Into this flange fits 55 the end of a cylindrical casing G, the casing being closed at its outer end, except that it has an opening to pass over the rod C. Screwing onto the outer end of the rod C is a butterfly-nut H, which clamps the casing in 60 place.

Through the cylindrical casing G on the front side is a slot g, extending nearly the length of the casing. Through this slot extends the flexible strip J, on which is written 65 or printed the telephone-directory desired. The inner end of this strip winds around the spool D in the opposite direction from the spring E, wherefore the spring tends to wind up the strip. At the extreme outer end of 70 the strip is a bar j, limiting the inward movement of the strip.

In the normal position of the parts the strip J is entirely wound up within the casing and the slot g is covered by the bar j. Thus the 75 structure is very tight and substantially dust-proof. Moreover, the directory is normally out of sight, which is a great advantage not only on account of neatness and cleanliness, but because the telephone user frequently does 80 not care to have his private list of calls exposed to view.

When the user desires to look up a call, he simply takes hold of the bar j and pulls the strip out until he comes to the name he is 85 looking for. The casing adjacent to the slot makes a guide across the strip, and the eye resting on this point as the strip is drawn out will allow the drawing out of the strip very rapidly without danger of missing the name 90 wanted. If desired, the capacity of the strip may be increased by writing the directory on both sides thereof.

The slot g extends to the open end of the cylindrical wall G, which allows the casing to 95 be drawn off when the nut C is removed. This allows the strip J to be removed and replaced as desired.

We claim—

An attachment for telephones consisting of a bracket, a rod projecting therefrom, a spool journaled on said rod, a casing composed of 5 a tubular member surrounding the spool and having a longitudinal slot extending from its inner end, a flexible strip secured to the spool and passing through said slot, means for turning the spool to wind up the strip within the 10 casing, and means carried by said rod for re-

movably securing said casing in place, substantially as described.

In testimony whereof we hereunto affix our signatures in the presence of two witnesses.

FRANK H. CHAMBERLIN.
RAYMOND H. COLEMAN.
